UNITED STATES PATENT OFFICE.

WILLIAM J. CROSTON, OF LAWRENCE, MASSACHUSETTS, ASSIGNOR OF SIXTY ONE-HUNDREDTHS TO WILLIAM H. DWELLY, OF BROOKLINE, MASSACHUSETTS.

PROCESS OF SCOURING OR CLEANING WOOL.

1,006,726.

Specification of Letters Patent. Patented Oct. 24, 1911.

Application filed February 8, 1911. Serial No. 607,308.

To all whom it may concern:

Be it known that I, WILLIAM J. CROSTON, a citizen of the United States, residing in Lawrence, county of Essex, and State of Massachusetts, have invented an Improvement in Processes of Scouring or Cleaning Wool, of which the following description, in connection with the accompanying drawings, is a specification, like letters on the drawings representing like parts.

This invention relates to a process for scouring or cleaning wool and especially those pieces of wool which are marked when on the sheep to identify the latter.

The sheep are now commonly marked with paint, tar and pitch, and when the wool is sheared from the animal the marked parts are cut off separately and sold for waste, being known to the trade as paint clips. In practice, the paint clips are accumulated, and frequently wool marked with all three materials are mixed together.

The present invention has for its object to remove the materials used for marking, so that the waste wool may be freed and cleansed from the same and what is now a waste material may be converted into a highly useful product. For this purpose, the marked wool is subjected to the action of a solution containing ingredients which will effectively free the wool from the materials used to mark the same, and I have obtained excellent results with a solution composed of benzin, alcohol and bisulfid of carbon, preferably in the following proportions, to wit:—7 parts benzin 86 proof, 5 parts methyl alcohol, and 3 parts bisulfid of carbon. The marked wool or paint clips are put into this solution and subjected to heat, which may be imparted by a water bath brought to boiling point.

To render the action of the solvent effective in the least possible time, the wool while saturated with the solvent is subjected to pressure so as to disintegrate or crush the marking material and open it up as it were, so that the solvent can readily reach the wool and thereby effect the separation of the marking material from the wool without dissolving the entire mass of the marking material. This separation of the marking material from the wool when subjected to pressure usually takes but a few minutes, and may be effected by the operator kneading or pressing the wool in the bath by hand,

after which the wool is agitated or shaken to mechanically separate the undissolved marking material from the wool. This shaking may be effected in the bath of solvent, after which the wool thus freed from the marking material is removed from the solvent and subsequently washed with soap, and water in any suitable or desired manner and as now commonly practiced in scouring wool.

The disintegration or opening up of the mass of marking material may be effected in the bath or it may be effected outside of the bath, in which latter case the wool is again subjected to the action of the solvent either in the same bath or in a second bath.

The wool thus treated is rendered fit to be used for all the purposes for which unmarked wool is used, and the cost of treating the now waste product is so small as to enable the treated wool to be sold at a very material profit.

In some instances, the waste wool which is accumulated is marked with all three of the above materials, to wit: paint, pitch and tar, and in other instances, with only two of the same materials, and while I prefer to use as a solvent the three ingredients above specified, I do not desire to limit the invention in this respect, as a very effective solvent solution may be made by the combination of the bisulfid of carbon with either benzin or alcohol.

I may prefer to use methyl alcohol, but I do not desire to limit the invention in this respect, as ethyl alcohol may be used instead thereof.

I may prefer to dry the wool after it has been subjected to the solvent bath and agitate the same and free it from the dirt, sand, etc., before washing the same with the soap and water, but I do not desire to limit the invention in this respect, as the wool may be taken from the solvent bath and directly subjected to the washing action of the soap and water.

The solvent for the paint herein shown has no injurious effect upon the wool; that is, it does not in any manner injure or kill the fiber of the wool.

The process above described, may be practiced on a commercial scale with an apparatus such as shown in section in the drawing, wherein 10, 12 represent two vats or vessels arranged in close proximity to each

other. Each of the vessels 10, 12, is provided with a false bottom 13, which forms a chamber containing water 14, which is heated by a steam pipe 16. Above the false bottom 13 the vessel is open and contains a bath 17 of solvent above described, and a perforated partition or bottom wall 18 below the level of the solvent bath 17, and upon which the wool clips 20 are supported. 5

10 The wool clips 20 are fed into one end of the vessel 10 and are moved through the bath of solvent in the vessel 10 by suitable means, herein shown as rakes 21, 22, which are eccentrically connected with disks 23, 15 24, designed to be rotated in any suitable manner.

10 The rakes 23, 24 serve to agitate the wool clips and feed it through the solvent bath in the vessel 10 to the squeeze rolls 25, 26 20 of known construction, which are located at the delivery end of the vessel 10.

10 The squeeze rolls 25, 26, serve to subject the wool clips saturated with the solvent to pressure to crush or disintegrate or open 25 up the paint or other marking material, and put it into effective condition to be separated from the wool by the solvent bath in the vessel 12, through which the partially treated wool clips are fed by the rakes 21, 30 22, therein, and fed out thereof by the squeeze rolls 25, 26, which serve to express the solvent from the wool, and place the wool in condition for the washing machine not herein shown, but which may be such 35 as now commonly used for scouring and cleansing wool. During the passage of the wool clips through the vessel 12, they are opened up and agitated by the rakes 21, 22, and the marking material, which is crushed 40 by the squeeze rolls 25, 26, of the vessel 10, is mechanically separated and drops through the perforated plate 18 in the vessel 12 onto the false bottom 13 thereof, from which the marking material may be removed from 45 time to time.

I have herein shown one form of apparatus for practicing the process of treating marked wool clips, but I do not desire to

limit the invention to any particular form of apparatus.

50 The perforated bottom 18 may be made in sections and rest upon cleats 30 on the sides of the vessel or vat, so that the perforated bottom may be readily removed to cleanse the bottom of the chamber containing the solvent, which latter may be drawn off through an outlet pipe 31.

Claims.

1. The process of freeing wool clips from materials with which they are marked, which 60 consists in subjecting the marked wool to the action of a solvent containing benzin, alcohol and bisulfid of carbon, subjecting the wool thus treated to mechanical pressure to disintegrate the marking materials, 65 and agitating the wool thus treated to mechanically separate the marking materials from the wool, substantially as described.

2. The process of freeing wool clips from materials with which they are marked, which 70 consists in subjecting the marked wool to the action of a solvent containing bisulfid of carbon and alcohol, subjecting the wool thus treated to mechanical pressure to disintegrate the marking materials, and agitating the wool thus treated to mechanically 75 separate the marking materials from the wool, substantially as described.

3. The process of freeing wool clips from materials with which they are marked, which 80 consists in subjecting the marked wool to the action of a solvent containing bisulfid of carbon and benzin, subjecting the wool thus treated to mechanical pressure to disintegrate the marking materials, and agitating the wool thus treated to mechanically 85 separate the marking materials from the wool, substantially as described.

In testimony whereof, I have signed my name to this specification in the presence of 90 two subscribing witnesses.

WILLIAM J. CROSTON.
